TRUCK TANK

Augustine Davis, Jr., Cincinnati, Ohio

Application May 17, 1930. Serial No. 453,125

9 Claims. (Cl. 220—86)

One part of the invention relates to an improved arrangement for hose-filling, that is to say enclosed filling, of truck tanks. In this connection objects of the invention are to provide a fire-walled device adapted to receive a hose and to conduct a solid stream of liquid from the filling hose to a point near the bottom of the tank, and to support this device in the manhole in such manner that it can be lifted out and that it does not require modification of the manhole cover or interfere therewith or with its locking mechanism or other parts carried by the cover.

The invention employs a fire-wall reducer or inner closure, and in the lower part of this reducer, which is preferably of a truncated conical form or of other dished shaped extending downward in the upper part of the tank, a fill-tube is fixed, the top of this tube projecting upward for a distance in the depression formed by the reducer and being provided with means for coupling a hose when the manhole cover is open. By reason of the manner in which this tube is supported, its hose coupling end is accommodated below the cover, in the space between the cover and the reducer.

The lower end of the fill-tube is guarded by a cage having fire-screened openings of large area through which the liquid introduced through the tube enters the general interior of the tank. The fill-tube preferably has a slip-joint connection with the top of this cage so that the tube can be withdrawn, leaving the cage in place. Provision is made for fire-screened openings at the top of the reducer and also at its lower end outside of the connection collar. These openings vent air and vapor while the tank is being filled, and the lower fire-screened opening also provides for draining into the tank any liquid which would otherwise be caught in the basin of the reducer around the upper end of the filling-tube.

Other features of the invention will become apparent as the specification proceeds.

In the accompanying drawings forming part hereof:

Fig. 1 is a fragmentary view in vertical section showing the invention applied to a tank, a portion of the tank and the filling structure between the top and bottom being broken out; and

Fig. 2 is a sectional plan taken on the line 2—2 of Fig. 1.

The tank 2 has a flanged-up manhole opening 3 in its top, and welded to the tank-shell around the opening there is a ring or frame 4, to which a manhole cover 5 is applied. This cover may be

hinged as shown or it may be entirely removable to afford entrance by a person into the tank. The cover is shown as provided with locking devices 6 below its under side to engage an S-shaped lip 7 bent inward from the top of the frame 4, and at its center the cover carries a vent device 8, which may be rotatable and connected with the locking bars 6 so that by turning the vent device the bars can be projected or retracted. Similar features are disclosed in the application of Paul S. Shield, Serial No. 201,059, filed June 24, 1927, and do not require special illustration since they form no part of this invention and since other means for securing the manhole cover in closed position may be employed.

As in the Shield application, a ring 9 of angular section is welded to the frame 4 to afford an inwardly projecting ledge 10 intermediate the height of the frame, and as in said application this ledge serves as a support on which rests the out-turned periphery 11 of an inverted truncated conical reducer 12, but this reducer, instead of serving as a funnel entrance to a broad tube for open, gravity filling as in the said application, here becomes a dropped support for a narrow fill-tube 13, which is designed to conduct a solid stream of liquid from a filling hose, which can be connected with this tube when the cover is opened.

A ring 14 of channel section is preferably welded into an opening in the lower end of the reducer, to constitute a part thereof, and within this ring the fill-tube is welded. The top of the fill-tube projects for a substantial distance above the low part of the reducer and includes a heavy-walled collar 15 which is welded to the tube and is formed with an external screw thread, on which is screwed the fixed element 16 of a quick-acting hose coupling. The provision thus made for the connection of a filling hose lies within the chamber between the reducer 12 and the cover 5 when the latter is closed. Any standard or suitable form of hose coupling may be employed.

The parts 9, 12 and 14 form a fire-wall extending across the manhole, from the frame 4 to the fill-tube 13, and the latter is a tubular fire-wall extending practically to the bottom of the tank.

As in the Shield application, one or more vent openings 17 are formed in the ring 9 at the top of the reducer 12, these openings being guarded by fire-screens 18. The ring 14 is also provided with one or more vent openings 19, likewise covered by fire-screens 20. This ring could be made in one piece with the reducer, but the provision of a ring made of a separate piece is advanta-

geous since it enables the same reducers to be carried in stock by the manufacturer to take either the narrow-fill-tube for hose filling as in the present application or a broad tube for gravity filling as in the Shield application, and the ring is also a strong part in which to locate the screened openings 19. These openings will drain into the tank any gasoline which may get into the basin of the reducer.

10. The lower portion of the tube 13 enters and passes downward within a cylindrical cage 21 of much larger diameter, the upper head 22 of this cage having a flanged opening 30 in which the tube fits frictionally, forming a slip joint. Large 15 openings 23 are cut in the side of this cage and are covered by a fire-screen 24, which in turn is covered by a heavy protective metal mesh 25. Another opening 26 in the bottom of the cage, guarded by a fire screen 27, allows the cage to be 20 entirely drained when the tank or a compartment thereof is emptied.

The cage is preferably secured in the lower part of the tank by bolted connections 28 between lugs welded to the sides of the cage and to the 25 bottom of the tank, respectively. The fill-tube can therefore be withdrawn without disturbing the cage, but the latter can also be removed by taking out the bolts.

Fastenings 29 on the ledge 10 engage over the 30 periphery of the reducer 12, so as to hold the filling structure firmly in place but in a removable manner. When the cover 5 is opened and these fastenings are released, the reducer and fill-tube can be lifted out, leaving the manhole unob- 35 structed.

An indicator may be provided in the following manner:

An opening is made in the reducer at a distance from the fill-tube, and in this opening a 40 small indicator tube 31 is welded so that the upper end of the tube projects into the chamber above the reducer and below the cover, while the major part of the tube extends downward a foot or so into the interior of the tank. The lower 45 end of this indicator tube is covered by a fire-screen 32, which allows the gasoline to rise upward in the tube as the filling of the tank proceeds but prevents flame from striking into the tank through the indicator opening.

50. A float 33 in the indicator tube ascends with the liquid and causes an indicator rod 34 connected to the float to rise upwardly above the reducer, giving ample warning to the attendant before it is necessary to cut off the supply of gasoline to avoid overfilling. The indicator rod is 55 guided in a hole in a cross-piece 37 at the top of the indicator tube, and this piece has an overhanging lug 35 beneath which the laterally bent end 36 of the rod can be turned to hold the rod 60 and float down when the filling operation is completed. The indicator is then entirely below the cover 5.

While the preferred form of the invention has been described in detail, it will be understood 65 that the embodiment is illustrative, and that various changes are permissible without departing from the invention as set forth in the claims.

I claim:

70. 1. In a vehicle tank having a manhole and a manhole cover, a fire-wall reducer removably supported in the manhole of the tank below said cover, a fill-tube entirely within the tank secured in said reducer and extending to a point near the bottom of the tank, the upper portion 75 of said fill-tube rising from the reducer, and

means within the tank, at the top of the fill-tube and beneath the cover for coupling a hose when the manhole cover is open.

2. In a vehicle tank having a manhole opening in the top, the combination of a fixed frame surrounding said opening, a manhole cover applied to said frame, a fire-wall reducer within the tank beneath said cover, said reducer being supported removably at its periphery in said frame and extending downward to form a depression, a fill-tube entirely within the tank secured in the lower part of said reducer and extending to a point near the bottom of the tank, the top of said fill-tube rising within said depression, and means on the top of the fill-tube for coupling a hose when said manhole cover is open. 80 85 90

3. In a vehicle tank having an opening in the top, a fixed frame surrounding said opening, and a cover applied to said frame, a fire-wall reducer within the tank beneath said cover, said reducer being removably supported at its periphery in said frame so that it can be lifted out and extending downward to form a depression, a fill-tube secured in the lower part of said reducer 100 and extending downward to a point near the bottom of the tank, the top of said fill-tube projecting upward in said depression and carrying a hose coupling element, and fire-screens guarding openings at the top of the reducer and also 105 at the lower portion of the same, the lower fire-screened opening serving to drain liquid into the tank. 95

4. In a vehicle tank having a manhole provided with a cover, a truncated conical fire-wall 110 reducer hung in said manhole within the tank so that it can be lifted out to afford ingress into the tank, a ring fixed in the lower end of said reducer, a fill-tube secured in said ring and extending to a point near the bottom of the tank, 115 a screw-threaded collar secured to the upper end of said fill-tube and projecting upward within the depression of the reducer, and a hose coupling element applied to said collar. 120

5. In a vehicle tank having an opening in the top provided with a cover, a truncated conical fire-wall reducer hung within the tank in said opening below the cover so that it can be lifted out, a ring fixed in the lower end of said reducer, and a fill-tube entirely within the tank 125 fixed in said ring and extending to a point near the bottom of the tank, the top of said fill-tube projecting upward within the reducer and carrying the fixed element of a hose coupling, said ring having an opening and a fire-screen guard- 130 ing said opening. 135

6. In a vehicle tank having an opening in the top provided with a cover, a fire-wall reducer hung within the tank in said opening, said reducer being supported removably at its periphery 140 so that it can be lifted out through the opening, a fill-tube entirely within the tank secured in said reducer and extending to a point near the bottom of the tank, the top of said fill-tube projecting within the reducer and carrying the fixed 145 element of a hose coupling, and means providing a fire-screened opening through the lower portion of the reducer to drain liquid from the reducer into the tank. 150

7. In a vehicle tank having an opening in the top provided with a cover, a fill-tube entirely within the tank supported in said opening and extending to a point near the bottom of the tank, a fire-walling below the cover extending from the upper part of said fill-tube to the walls 150

- of the tank, means removably supporting said fire-wall and said fill-tube so that they can be removed through said opening, said fire-wall provided with fire-screened openings, the 5 top of said fill-tube projecting upward from said fire-wall and carrying means beneath the cover for coupling a hose, and a cage in the lower part of the tank of larger diameter than the fill-tube into which the fill-tube descends, 10 said cage having fire-screened openings of large area through which liquid introduced through the fill-tube passes to the general interior of the tank.
8. In a vehicle having an opening in the top, 15 a fill-tube entirely within the tank extending to a point near the bottom of the tank, means removably supporting said fill-tube so that it can be withdrawn through said opening, and a cage held in the lower portion of the tank and

9. In a vehicle tank having an opening in its top and a cover for said opening, a fire-wall reducer in the tank hung removably in said opening below said cover, a fill-tube entirely within the tank secured in said reducer and extending to a point near the bottom of the tank, 85 the top of said fill-tube projecting upward within the reducer and having means for the connection of a hose, and a cage in the lower part of the tank into which the lower portion of the fill-tube extends, said cage having fire-screened openings of large area through which liquid introduced through said tube passes to the general interior of the tank.
- AUGUSTINE DAVIS, JR.
